C. C. McMANAWAY.

RAILROAD CROSSING.

APPLICATION FILED JULY 15, 1918.

1,287,063.

Patented Dec. 10, 1918.

FIG. 1.

UNITED STATES PATENT OFFICE.

CLARENCE C. McMANAWAY, OF COWDEN, ILLINOIS.

RAILROAD-CROSSING.

1,287,063.

Specification of Letters Patent. Patented Dec. 10, 1918.

Application filed July 15, 1918. Serial No. 244,976.

To all whom it may concern:

Be it known that I, CLARENCE C. McMANAWAY, a citizen of the United States, residing at Cowden, in the county of Shelby and State of Illinois, have invented certain new and useful Improvements in Railroad-Crossings, of which the following is a specification.

This invention relates to railways, and 10 more especially to crossings; and the object of the same is to produce a device of this class which when set for either track will result in practically continuous rails so as to eliminate the noise and jar as far as possible.

Another object is to provide for tempered elements at the point of crossing so as to reduce wear as far as possible.

Yet another object is to make provision 20 for the simultaneous change in the direction of the several elements to accommodate a train approaching on either track.

Details are set forth in the following specification and claims, and attention is 25 invited to the drawings wherein:—

Figure 1 is a diagrammatic plan view of this crossing complete.

Fig. 2 is an enlarged plan view of one of the points of crossing and its details.

Fig. 3 is a transverse section through the center of Fig. 2.

The numerals 1 and 2 designate the rails of one track, interrupted between their ends by short track sections 3, and the numerals 4 and 5 designate the rails of the other track interrupted by similar track sections 6, the said tracks in the present instance being shown diagrammatically in Fig. 1 as crossing each other at right angles and herein- 40 after described on this basis. Crossing elements are employed at the four points of intersection as seen in this view, but as they are duplicates we need consider but one as more fully illustrated in Figs. 2 and 3. The 45 contiguous ends of the rails 1 and 3 and the rails 4 and 6 are slightly spaced and the respective ends are connected by angle irons whereof each has arms 7 and 8 standing at right angles to each other, these arms being 50 connected by an interposed quadrant 9, and the several quadrants collectively making up a complete circle. The arms are by preference bolted as at 10 to the webs of the rails or rail sections and where the arms 55 lap the short sections 3 and 6 they prefer-

ably abut as indicated at 11 in Fig. 1. The rails and rail sections are laid on ties as usual and as not necessary to illustrate and describe.

Within each circle or ring made up of 60 the several quadrants 9 and the butt ends of the confronting rails is located a circular plug 15 preferably of steel or otherwise rendered extremely hard, the plug being cylindrical in contour and provided with an annular groove 16 into which the quadrant fits. The bottom of the plug at its axis 65 preferably has a conical socket rotatably mounted on a cone 17 at the center of a plate 18 which itself is suitably supported 70 as indicated in Fig. 3, and thus the plug is mounted for rotation and supported in its rotation both by the quadrants and the cone 17, while it is also supported by the plate 18 with sufficient strength to bear the load 75 to be placed upon it. The top of the plug is cut off flat as seen in Fig. 3, excepting for two transverse grooves or channels 20 and 21, formed at opposite sides of an interposed 80 portion of said upper face which will constitute the ball 22 of a rail, its size and shape corresponding with the ball of the rail with which it alines. While both grooves 20 and 21 are not absolutely necessary in all cases, I prefer in order that the 85 plugs shall be interchangeable to form them with both grooves so that the flange of the wheel may travel across the plug at either side of its ball 22. Means may now be provided for turning all plugs a quarter revolution simultaneously. For this purpose I 90 pivot links 23 to the several plugs at the point indicated at 24, and provide suitable mechanism for manipulating the links in unison. It is obvious that if the pivotal 95 point 24 in Fig. 2 be moved to the dotted position 25, the plug 15 will be given a quarter rotation and the ball 22 will then stand directly in alinement with the rails 1 and 3, and therefore the operative mecha- 100 nism (forming no part of the present invention) which actuates the several links, must be such as will give them this degree of movement in unison. In order to lock the plugs after they have been adjusted, I make 105 use of a bolt 26 entering a socket 27 in one side of the plug, and the latter is by preference provided with another socket 28 exactly ninety degrees from the first socket after the plug has been turned. Here again 110

mechanism must be employed for retracting and projecting the several bolts in unison. If the link-actuating mechanism is such as to lock the several links against movement after they have been shifted to turn the plug, the bolt 26 may not be absolutely necessary, but in order to be perfectly sure that the ball 22 of the plug is in strict alinement with the balls of either the two rails 4 and 6 or the two rails 1 and 3, I prefer to employ the locking mechanism.

When now a train approaches moving north or south in the diagram illustrated in Fig. 1, its wheels pass along the rails 4 and 5, across the balls 22, along the rail sections 6, across the other balls 22 and onward; and because of the close fit of the parts there is a minimum of noise and of jar. It is quite within the spirit of my invention that the 20 plugs shall be tempered or otherwise rendered extremely hard so that they will for a long time resist the strain thrown upon them as trains cross over them. When a train approaches from east or west, the 25 plugs will of course have to be given a quarter revolution so that the balls 22 will stand in the opposite position from that shown in Fig. 1. If the two tracks do not cross each other at right angles, then the throw 30 of the links 23 by the actuating mechanism must be regulated accordingly, and the sockets 27 and 28 in the balls will be regulated accordingly. I prefer that the bolt 26 shall move through a suitable guide opening 29 in one of the quadrants 9 so that its

tip shall be accurately directed into the socket which is opposite thereto.

The foregoing description and the drawings have reference to what may be considered the preferred, or approved form of 40 my invention. It is to be understood that I may make such changes in construction and arrangement and combination of parts, materials, dimensions, et cetera, as may prove expedient and fall within the scope 45 of the appended claim.

Having thus fully described my invention what I claim as new and desire to secure by Letters Patent, is:—

The herein described railway crossing 50 comprising two crossing interrupted rails whose contiguous ends are spaced, a set of angle irons whereof each comprises two arms at right angles to each other and connected by an interposed quadrant, means for securing the arms to the rails, a cylindrical plug having a peripheral groove slidably mounted on said quadrants and in its lower face a socket, a supporting plate underlying said plug and having at its center a conical 55 bearing engaging said socket, a ball extending diametrically across the upper face of the plug, and means for turning the plug to aline said ball with either line of rails.

In testimony whereof I affix my signature 60 in the presence of two witnesses.

CLARENCE C. McMANAWAY.
